TYPEWRITER ATTACHMENT FOR
MANIFOLDING

Robert J. Copeland, Toronto, Ontario, Canada

Application June 21, 1940, Serial No. 341,620
In Canada July 27, 1939

1. Claim. (Cl. 197—126)

The principal objects of this invention are to greatly facilitate the work and cost in connection with duplicate billing, and to provide a simple and inexpensive form of device for this purpose capable of being readily attached to a standard typewriter carriage.

A further and important object is to eliminate the necessity of individually inserting and removing the original and duplicator sheets and impression transfer medium to enable the operation to be carried out in a continuous and efficient manner without soiling of the operator's fingers and smudging of the original sheets.

The principal features of the invention reside in the novel construction and arrangements of parts whereby a special duplicator carbon or the like is supplied in a substantially automatic manner to the platen in conjunction with original and duplicating record sheets of continuous strip form, the arrangement being such that a negative impression of the typing is retained on the duplicate sheets from which numerous copies may then be produced on a duplicator machine.

A further and important feature resides in the novel provision of a guide plate which is independently supported on a guideway for movement in unison with the travel of the typewriter carriage and having a holder supported thereon for containing a supply of continuous interfolded sheets which are directed over the plate to the platen of the typewriter minimizing buckling of the continuous strips of sheets and ensuring more accurate guiding thereof to the platen.

Further and important features will be apparent in the following description.

In the drawings

Figure 1 is a perspective view of a device constructed in accordance with the present invention and showing its co-operative relation to the continuous original and negative impression sheets and special carbon sheet.

Figure 2 is a somewhat diagrammatic part sectional side elevational view of the attachment device mounted in co-operative association with a typewriter platen.

Figure 3 is a perspective view of the device shown in Figure 2.

Figure 4 is a miniature side elevational view of the complete assembly in co-operative relation to a typewriter.

Figure 5 is a part sectional elevational view on an enlarged scale and broken away in part of

one of the rotatable spindles for supporting the continuous special carbon sheet.

Figure 6 is a perspective detail in contracted form of a locking member for connecting the special carbon sheet with the spindle.

Figure 7 is a perspective view showing the completed original invoice and the negatively impressed duplicator sheet after separation from the continuous strip.

Figure 8 is a part sectional side-elevational view of a modified form of the present invention.

Figure 9 is a fragmentary plan view of the guide plate and supporting carriage of Figure 8.

Figure 10 is a perspective view of the guide plate and roller units of Figure 8.

Figure 11 is a perspective view illustrating a further modified form of apparatus embodying the principles of the present invention showing same in co-operative association with a standard typewriter.

Figure 12 is a part sectional side elevational view of the apparatus shown in Figure 11.

In billing or manifold work where an original typed sheet is required and a number of copies, it has been the practice to employ a special carbon sheet known to the trade as "Hectograph" which was required to be placed with its treated face in contact with the back of the original so that during the typing operation, the typed matter was negatively impressed on the undersurface of the original which was then used in connection with a duplicator machine in order to print the required number of positive copies from the negatively impressed surface of the original.

The use of the original in this capacity is objectionable not only because it carries a printed impression on the reverse side but also because it invariably becomes smudged during the process, and in many cases is rendered unfit for its intended purpose.

The present invention has been devised to eliminate the necessity of employing the original as a transfer or duplicating medium so that it can be taken fresh from the typewriter and forwarded immediately if desired, while a separate negatively impressed sheet, which may be of plain or unprinted character, will be retained from which the required duplicate copies are made.

The present invention further eliminates the necessity of the operator's fingers coming in contact with the treated surface of the special carbon sheet which is a frequent source of smudging of the original according to present practice.

In accordance with the form of the invention illustrated in Figures 1 to 7, a plate 1 of light sheet metal is provided which is bent intermediate of its length to present an inclined plane portion 2 and a substantially horizontal plane portion 3. This plate is adapted to be connected at its lower edge to a suitable portion of the carriage 4 of a typewriter 5 by means of suitable clip members 6 such as employed in connection with my United States Patent 2,070,042, granted February 9, 1937.

A roller support 7 similar to that used in the said patent is here shown contacting the underside of the plate portion 3 to support the same while permitting freedom of movement of the plate.

A pair of brackets 9 and 10 are secured to the plate portion 2 at opposite sides and between these brackets are rotatably supported in spaced relation a pair of spindles 11 and 12. The rotatable support of one end of the spindles in the bracket 10 is accomplished by a pair of stub shafts 13 and 14 provided with centering pin projections 15 as indicated in Figure 5 and also provided with a projecting pin drive extension 16 for non-rotative locking engagement with a notch 17 in the spindle.

The stub shaft or spindle 11 carries a pulley 18 adapted to be hand rotated by a crank 19 and a suitable belt or the like 20 is adapted to form a driving connection with the stub shaft 14 of spindle 12 through a pulley 21 mounted on the latter shaft for a purpose hereinafter referred to.

Retractable pivot supports 22 and 23 mounted in the bracket 9 have pin bearing projections 24 35 (Figure 5) for centering and bearing contact with the axial bearing recess 25 of the spindle, bearing engagement being normally maintained by inward pressure of the spring element 26.

A supply of special carbon paper, which may be of the type referred to and known to the trade as "Hectograph" and represented at 27, is adapted to be rolled on the spindle 11 in such a manner that when it is passed under the platen 28 of the typewriter and upwardly at the forward side thereof, the special treated or carbon surface thereof will be outermost, that is, on the side which is not contacted by the platen. The advance end of the special carbon strip 27 is adapted to be anchored to the spindle 12 and a suitable means for accomplishing this is here shown in the form of an elongated V-shaped retainer 28' which is adapted to be pressed into an elongated slot 29 in the spindle to retain the end of the carbon strip therein and a similar locking arrangement may be provided in connection with the spindle 11.

A pair of holders 30 and 31 are here shown supported in a stepped arrangement, one above and rearwardly of the other at a suitable distance rearwardly of the typewriter. The holder 30 is adapted to support a pack 32 of continuously inter-folded original invoice or record sheets 33, while the holder 31 is here shown supporting a pack 34 of continuous inter-folded duplicator sheets 35, which latter sheets may be of any suitable material and may be of a plain or unprinted nature, since according to the present invention they are adapted to receive and retain a negative impression of the typed original or record sheets and to be thereafter utilized in a duplicator machine in a well known manner for producing the desired number of copies therefrom.

The plate 3 is here shown provided with a

guide member 36 through which the continuous strips of sheets 33 and 35 are threaded with the former sheets uppermost so that as the respective sets of sheets are advanced downwardly over the incline plate 2 and about the platen 28, the plain or duplicator sheets 35 will directly overlie the specially treated surface of the carbon sheet 27 below the original invoice or record sheets 33.

In this way the original invoice will receive the direct impression from the typewriter and there will be simultaneously impressed on the rearward side of the duplicator sheets 35 a negative impression of the typed matter.

It will be further observed that the sheets 35, being interposed between the special carbon sheet 27 and the originals, will act as a desirable separating medium to prevent smudging or undesired marking of the reverse side of the original, and moreover the original will be free of any typed impressions on the reverse side thereof.

When the typing of each invoice has been completed the mating sheets 33 and 35 may be advanced until the transverse line of severance 37 has been raised clear of the platen which may be sufficiently far to properly position the next adjacent sheet for typing and the typed sheets may then be readily detached along the line 37, this detachment being further facilitated by the rounded or notched entry 38 provided at the end of the line of severance 37.

As the typing proceeds and the strips are advanced about the platen the continuous strip 27 will not only be unwound from the spindle 11 but will be continuously rewound on the spindle 12 by reason of the drive connection 20 previously referred to.

When the supply of the carbon sheet 27 has been exhausted from the spindle 11 and wound on the spindle 12 it is a very simple matter to rotate the spindle 11 by the hand crank 19 to rewind the carbon sheet.

In the form of the invention illustrated in Figures 8 to 12, a supporting frame 39 is provided in the form of parallelly-spaced rods or bars having upright portions 40 vertically adjustable in supporting brackets 41 where they are secured by clamping means 42.

The horizontal portions 43 of the bars 39 have transversely extending guideways 44 and 45 secured thereto in parallelly-spaced relation.

A plate member 3' has a portion horizontally overlying the guideways 44 and 45 and provided with spaced sets of guide rollers 46 on the underside engaging in rolling and guiding contact between the flanges of the guideways. The plate 3' has its forward portion sloping angularly downward to provide an inclined area 2'.

A rod 47 is rotatably mounted in brackets 48 secured adjacent the lower edge of the portion 2' and suitably held against axial displacement in the brackets.

Block members 49 are slidably mounted on the ends of the rod 47 and adapted to be secured thereto in adjusted relation by the clamping screw 50. Short rod members 51 are slidably adjustable in the blocks 49 in a plane right-angularly related to the axis of the rod 47 and are adapted to be secured in adjusted relation to the blocks by the clamping screws 52, the lower end of the rod 51 being turned into right-angular relation to parallel the rod 47 as indicated at 53 in order to slidably engage suitable surfaces of the typewriter carriage 4'. Thus by suitable adjustments of the clamped relation of the bars

51 to the rod 41 and to the carriage, the plate 3' may be made to travel with the typewriter carriage in its longitudinal travel with little or no loss of motion, while at the same time, the pivoting of the rod 41 in its plate brackets will permit the carriage to be raised and lowered in the normal typing operations without any material lifting thrust on the plate, this being further facilitated by providing suitable freedom of movement at the ends of the rods 51.

A holder 55 for the interfolded original and copy sheets 33 and 35 is suspended from the rearward portion of the plate 3' so that it angularly underhangs the carriage, the rearward edge portion of the plate being provided with a downwardly rounded lip 3" to permit the continuous strips to move smoothly thereover in being drawn from the pack 56 supported in the holder 55.

Referring now particularly to the structure shown in Figures 8 to 10, the plate 3' is provided with inturned lugs 57 and 58 arranged adjacent the rear and front edges in order to engage the edges of the continuous strips 33 and 35 to guide the strips accurately to the platen 28' of the typewriter.

The roller-supporting brackets 9' and 10' are here shown secured to the plate 3' substantially midway between the front and rear edges directly above the carriage support of the plate so that the load represented by the rolled strip of "Hectograph" material 27 carried by the rollers 11' and 12' will be carried directly by the roller supports 46 free of the typewriter carriage.

Referring now particularly to the modifications illustrated in Figures 11 and 12, the special rollers for supporting the "Hectograph" strip have been eliminated and in place thereof I have substituted a sheet 59 of the "Hectograph" type, to the upper edge of which I provide an extension 60 of any suitable grade of paper or the like which is free of carbon or "Hectograph" material so that the operator may grasp the portion 60 to manipulate the active portion 59 without any possibility of soiling the fingers. This further effects an economy.

A guiding and supporting strip 36' is looped over the rearward edge portion of the plate 3' and supports a spring-return device 61 which may be of the type set forth in my earlier patent referred to herein.

A length of tape 62 or other suitable flexible material is adapted to be drawn outwardly against the tension of the spring-return device 61 and carries a clip 63 which is adapted to releasably grip the extension 60 of the special carbon sheet 59 to effect the retraction thereof as will hereinafter appear.

A slotted folding strip 64 is pivotally mounted on the supporting member 36' and conforms substantially to the contour of the plate 3', a stop member 65 being adjustably mounted in the slot of the strip and adapted to be clamped in any desired position by the clamping means 66. The clip member 63 carries a finger portion 63' which is adapted to engage the stop member 65 on the return movement of the tape to arrest the same with the special carbon sheet 59 in predetermined relation to the platen preferably with the lower edge thereof in substantial register with the advance edge of the sheets 33 and 35.

Thus on the typing of the various items on the original sheet the secondary or duplicator sheet 35 will receive from the special sheet 59 a negative impression of the typing in a manner similar to that defined in connection with the use of the rolled strip 27.

When the typing has been completed and the original and duplicator sheets advanced to the point where they may be readily severed by tearing along the line 37, the release of the platen tension devices of the typewriter will permit the spring tension device 61 to return the special carbon or "Hectograph" sheet 59 back to its original point of commencement as determined by the stop 65 and the sheets 33 and 35 may be torn off and typing commenced on the next adjacent set of sheets.

It will be apparent that with the forms of the invention defined it will not be necessary for an operator to handle the actual carbon strip 27 or the carbon sheet 59 so that undesirable marking of the typed sheets by smudge deposits from the fingers due to contacting of the carbon sheet will be definitely avoided.

25 The duplicator sheets 35 are here shown provided with finger notches 67, preferably leading from the line of severance which will facilitate ready separation of the detached sheets 33 and 35.

30 I am aware that sheets in continuous strip form are now in extensive use for the making of originals and the direct impressing of positive carbon copies, but so far as I am aware it has not previously been proposed to utilize a continuous strip supply in connection with the production of originals and simultaneous duplication of a separate master negative copy for subsequent reuse independent of the original as a duplicating medium.

35 The present invention is of simple form, eliminating the necessity of providing complicated machines for this purpose and a considerable saving in the operator's time will be effected and a general reduction in the cost of carrying out 40 this special phase of business.

45 What I claim as my invention is:

In a device of the class described in which original and duplicator sheets are directed to the platen of a typewriter in continuous strip form, 50 means for imparting a negative impression to the duplicator sheet for use in subsequent duplicating operations as the original sheet is being typed, and means operable in unison with the typewriter carriage for supporting and guiding said sheets and said latter means, comprising a 55 guide plate movable in unison with the typewriter carriage, said means for imparting the negative impression comprising a sheet of special duplicating medium, retractile means connected 60 with said special sheet for drawing the same rearwardly of the typewriter platen on completion of the typing operation, a strip overlapping said plate and the sheets thereon, and stop means adjustable longitudinally of said strip for 65 co-operation with said retractile means to arrest the retraction of said special strip at a predetermined point.

ROBERT J. COPELAND.
